UNITED STATES PATENT OFFICE.

EMIL J. CARROLL, OF CINCINNATI, OHIO, ASSIGNOR TO THE AMERICAN LAUNDRY MACHINERY COMPANY, OF CINCINNATI, OHIO, A CORPORATION OF OHIO.

EXTRACTOR CONTROL.

Application filed July 22, 1921. Serial No. 486,717.

This invention relates to centrifugal extractors such as are used for extracting water or moisture from clothing, textile fabrics, or for various similar uses in laundries, dry cleaning establishments, textile mills or the like. The invention has to do with the controlling devices, its object being to provide an improved extractor which is electrically driven and which may be braked 10 by reverse phase or dynamic braking effects; to provide safety devices for preventing access to the rotating basket when the machine is running; to automatically stop the machine at the conclusion of a definite period 15 of time, and to inter-relate or inter-connect the safety devices and control circuits so that the extractor will be largely, if not wholly automatic in operation. Another object of the invention is to provide an extractor 20 having a safety cover and control devices and circuits arranged whereby said cover is released when the machine is at rest, whereby the closing of said cover starts the machine and locks the cover closed, in which the machine is automatically electrically braked after the conclusion of a definite period of time and finally wherein the mechanism releases and automatically opens the safety cover.

25 Further objects of the invention are in part obvious and in part will appear more in detail hereinafter.

In the drawings, Fig. 1 represents a front elevation of one form of structure embodying the invention, the safety cover being shown in closed position; Fig. 2 is a front elevation on a larger scale, showing the cover controlled and controlling devices; Fig. 3 is a detail plan view of the device as 30 shown in Fig. 2; Fig. 4 is an end view of the cover locking mechanism; Fig. 5 is a sectional elevation on the line 5—5, Fig. 2; Fig. 6 is a detail elevation of the upper end portion of the extractor spindle and illustrating the driving connection to the timing mechanism; Fig. 7 is a detail plan view of the timing device; Fig. 8 is a detail end view on a larger scale of the timing contacts; Fig. 9 is a detail sectional view on the line 9—9, Fig. 6, illustrating a safety finger; and Fig. 10 is a diagrammatic view illustrating the electrically controlled devices and circuits.

The invention may be applied to any form of electrically driven extractor. The drawings show for this purpose an extractor comprising a stationary outer frame 1 in which is suspended for proper oscillating movement in any direction a hollow curb or casting 2 carried by the swinging curb frame 3. In said curb frame is suitably journalled 55 the extractor spindle 4 provided within the curb with the usual basket to receive the material to be extracted, which basket has a perforated or foraminous outer wall 5. The basket is rotated by an electric motor 60 which is directly connected to said spindle. As illustrated, the motor comprises a field frame or stator 6 carried by a cross bar or support 7 of the curb frame, and the field of 65 which co-operates with an armature or rotor 8 attached to the spindle. Both the field frame or stator and armature or rotor of the motor swing with the oscillating curb frame 3, so that the shocks and jars of unbalanced 70 loads are not communicated to the motor 75 and the drive is by true torque around the axis of the basket spindle with the motor clearance maintained constant.

Access to the opening through the top of 80 the curb to the basket is permitted or prevented by a movable cover 10 which lies at the front of the machine and is in the form of a sheet metal gate having a conveniently located handle for its manipulation, as 85 shown in Fig. 1. This cover or gate has vertical movement. In its lowest position, shown in Fig. 1, it prevents the operator from gaining access to the rotating basket, while in its upper position such access is 90 permitted. The cover is supported by chains or cables 11 connected to laterally extending arms 12 and which cables pass over idle pulleys 13 and are each provided with 95 a counterweight 14 travelling up and down in a hollow tubular guard 14^a. The arms 12 are preferably provided with anti-friction members, such as rollers 15, which travel along guides 16 and thereby control and guide the cover in its vertical movement.

The parts are preferably so arranged that 100 the cover may be automatically locked in its lowest position and such cover when moved to its lower position also actuates the starting switch for producing one cycle of operations of the extractor. For this purpose 105 the stationary frame 1 of the machine car-

ries the pivoted latch 17, Figs. 2 and 4, the vertical arm of which is of hook form and adapted to latch over an extended portion of one of the door arms 12, the lower edge 5 of said arm being beveled, as at 18, so that it will pass the latch in its downward motion and readily reach the locking position shown in Fig. 4. The horizontal arm of the latch 17 is pivotally connected to the core 10 of a solenoid 20 and the parts are normally held in the locking position shown in Fig. 4 by a light compression spring 21. When said solenoid is energized its core moves downwardly and turns the latch 17 15 until the cover is released, whereupon said cover immediately rises automatically to its open or upper position.

22 represents any suitable form of switch for closing the starting circuit, the details 20 of said switch being immaterial. The switch parts are actuated by depression of a button 23 actuated by a cam arm 24 on a shaft 25 provided with another arm 26 lying beneath the door arm 12. Then the 25 door is moved to its lower position, arm 12 depresses lever 26 and closes the starting switch.

The apparatus is also provided with automatic timing mechanism capable of automatically stopping the machine after the conclusion of a reasonably definite period of time. For this purpose the upper end of the basket spindle has secured thereto a bevel gear 30 adapted to drive a bevel gear 31 on a shaft 32 which is connected by any suitable universal or flexible joint 33 to drive a shaft 34, Fig. 7, which through suitable gearing, marked generally 35, rotates the timing drum 36. The timing gears 35 are 30 suitably interchangeable and adjustable so as to produce any desired amount of rotation of the drum 36 for a given number of revolutions of the basket spindle. In other words, by proper selection and adjustment 40 of the timing gears the timing drum may be made to turn through one complete revolution in approximately five, ten, fifteen or twenty minutes or any other period as desired. The timing drum comprises an insulated body member 37 carrying a peripherally extending conducting segment 38 in which is a longitudinally extending insulated segment 39. Co-operating with said drum are two brushes 40 the contact ends 45 of which lie opposite each other so that both will reach the insulated or blank segment 39 at the same time and thereby open the control circuit, as will appear hereafter.

60 The electric motor may be either an A. C. or a D. C. motor. If the motor is of the D. C. type the basket spindle will be braked by dynamic braking effect. For purposes of illustration the drawings show a three phase A. C. motor, and the braking effect is secured by reversing two of the service leads.

Therefore, suitable means is provided for preventing reversal of the motor by continuance of the supply of current thereto after the spindle has come to rest. For this purpose the spindle carries a friction finger 41. 70 Fig. 9, mounted on a ring 41^a held frictionally by the spring 41^b on a spindle, so that said finger tends to always move or turn in the direction of rotation of said spindle. When the basket rotates in the normal or 75 driving direction this finger is moved into engagement with a contact 42 and thereby completes a control circuit, but as soon as the spindle begins to rotate in the opposite direction finger 41 moves away from the 80 contact 42 to a fixed insulated stop 42^a and thereby opens the control circuit and cuts off the flow of current to the main circuits of the motor so that said motor cannot be driven in the reverse direction. 85

Fig. 10 represents the control devices and electric circuits for the extractor. These devices and circuits are as follows: 50, 51, 52, and 53 represent respectively the forward relay, the reverse relay, forward switch and 90 reverse switch. The coil of the forward relay 50 actuates normally closed contacts 54 and normally open contacts 55. The reverse relay 51 actuates the normally closed contacts 56 and normally open contacts 57. 95 The forward switch 52 actuates two sets of normally open contacts 58 and a switch arm 59 which co-operates with normally closed contacts 60 and normally open contacts 61. The reverse switch 53 actuates two sets of 100 normally open contacts 62 and also actuates a switch arm 63 which co-operates with normally open contacts 64 and normally closed contacts 64^a. 65 represents the main switch which controls the flow of current to 105 the motor M and also the flow of current through the various control circuits. 22 on the diagram is the starting switch illustrated in Fig. 5 and actuated by closing of the safety door or cover, while 20 is the 110 solenoid which actuates and releases the latch, and 41 indicates the friction finger for preventing motor reversal. 66 is the stop button and 67 and 68 are respectively 115 a white or stop light and a red or running light.

The operation is as follows: Let us assume that the extractor basket is at rest with the door open. In this position of the parts there is one live circuit from the point 69 120 of the main switch, which will be assumed to be positive, by way of wire 70 through the normally closed contacts 54 and white stop light 67 and back by way of wire 71 to the point 72, which will be assumed to be negative. The illumination of this white light indicates to the observer that the machine is idle and directs him to empty and reload the basket and start it through another cycle. When the machine is reloaded 125 130

the cover or gate is pulled down to its lowest position, in which it is automatically locked by the latch 17. The door arm 12 also closes the switch 22 thereby establishing a circuit as follows: From 69 through wire 73 and switch 22, stop button 66, contacts 56, coil 52, contacts 64^a and back by way of wire 74 to negative. The effect of this circuit is to energize the coil of the forward switch 52, thereby closing the contacts 58 and establishing the main circuits through the motor to rotate in the forward direction. The control circuit through coil 52 just described includes contacts 64^a, so that said circuit cannot be completed unless the reverse switch is in normally open position. Actuation of the forward switch also shifts switch arm 59 from contacts 60 to contacts 61, so that it is impossible to close a circuit through the reverse switch which is in series with contacts 60, unless and until the forward switch is de-energized. As soon as the forward switch closes another circuit is established as follows: From 69 through wire 73, switch 22, contact 75, wire 76, contacts 61, wire 77, point 78, forward relay 50 to wire 74 and then to negative. Energization of the forward relay 50 opens contacts 54 and cuts out the stop light 67. At the same time it closes contacts 55, thereby establishing a direct connection from positive point 69 through 22, 75, 81, wire 79, contacts 55, forward relay 50, wire 74 to negative. Another circuit is established from a point 78 by way of wire 80, running light 68, wire 71 to negative. The running light is illuminated, indicating that the basket is turning. In the running position the safety cover is locked in its lower position by the latch 17 and cannot be released unless and until the solenoid 20 is energized.

The basket runs in the forward direction, thereby turning the friction finger 41 into engagement with its stop 42, and also drives the timing mechanism until either the stop button 66 is manually actuated, as for inspection purposes, or the timing mechanism completes its operation and the contacts 40 thereof reach the blank segment 39. This switch 39, 40 is in the same circuit as the stop button 66 and operates in the same manner. If the timing switch opens the circuit, the coasting of the basket before it comes to rest is sufficient to carry the contacts 40 onto the live segment so that the parts will be in condition for another operation.

When either the stop button 66 or the timing switch 39, 40 is opened the coil 52 is de-energized, whereupon the forward switch contacts 58 are opened and the switch arm 59 moves from contacts 61 to contacts 60 establishing a circuit as follows: From 69 by way of wire 73, switch 22, point 75, point

81, wire 79, contacts 55, point 78, wire 77, left contact 61, contacts 60, reverse switch 53, friction finger 41, and wire 71 to negative. This circuit includes the reverse switch 53 and friction finger 41. Its effect is to close contacts 62 and reverse two of the main circuits through the motor, thereby producing a braking effect. Actuation of coil 53 opens contacts 64^a and closes contacts 64, but no circuit is yet established through the solenoid 20. Closing of the switch 64 establishes a circuit through the reverse relay 51 as follows: from the point 81, to which current comes by way of wire 76, through wire 82, contacts 64, wire 83, contact 57, wire 84, reverse relay 51, wire 74 to negative. Actuation of the reverse relay 51 opens contacts 56 and closes contacts 57 so that the reverse relay coil 51 is maintained energized by current coming from the point 81 by way of wire 85, contacts 57 and wire 84. When the friction finger 41 opens, the reverse switch 53 is de-energized, which opens contacts 62 and cuts off the main circuit to the motor. Contacts 64^a are also closed and contacts 64 are opened. Closing of contacts 64^a completes the circuit through the trip solenoid 20 as follows: From 69 through wire 73, switch 22, point 75, wire 76, point 81, wire 85, contacts 57, wire 83, contact 64, wire 86, trip solenoid 20, contacts 64^a, and wire 74 to negative. Energization of the trip-solenoid 20 turns the latch 17 and releases the door, which is raised by its counterweights. When the door rises the door switch 22 opens, which de-energizes the solenoid 20 and allows the latch to return to normal position. At the same time the stop light 67 is again illuminated, the parts being then ready for another cycle of operations.

What I claim is:

1. A centrifugal extractor, comprising a rotatable basket, a safety cover therefor, power means for rotating said basket, means controlled by said cover for rendering said power means effective or ineffective upon said basket, latching means for said cover, and timing means for effecting operation of said latching means at the conclusion of the extracting period.

2. A centrifugal extractor, comprising a rotatable basket, a safety cover therefor, an electric motor for rotating said basket, circuit connections for said motor controlled by said cover, a latch for said cover, and timing means for effecting operation of said latch at the conclusion of the extracting operation.

3. A centrifugal extractor, comprising a rotatable basket, a safety cover therefor, a motor for rotating said basket, means whereby closing movement of said cover causes completion of an operating circuit to said motor, and timing means for changing the

circuit connections to said motor to produce a braking effect.

4. A centrifugal extractor, comprising a rotatable basket, a safety cover therefor, a motor for rotating said basket, means whereby closing movement of said cover controls operation of said motor, timing means for changing the circuit connections to said motor to produce a braking effect, and means whereby the flow of current to said motor is cut off when the direction of rotation of said spindle reverses.

5. A centrifugal extractor, comprising a rotatable basket, a safety cover therefor having a normal tendency to open, power means for rotating said basket, means controlled by said cover for rendering said power means effective or ineffective upon said basket, latching means for holding said cover closed, and timing means for actuating said latching means at the conclusion of the extracting period.

6. A centrifugal extractor, comprising a rotatable basket, a safety cover therefor, cover opening means, power means for rotating said basket, and timing means whereby said cover is automatically opened at the conclusion of the extracting period.

7. A centrifugal extractor, comprising a rotatable basket, a safety cover therefor having a normal tendency to open, power means for rotating said basket, means controlled by said cover for rendering said power means effective or ineffective upon said basket, means for holding said cover in closed position, and means for automatically releasing said cover.

8. A centrifugal extractor, comprising a rotatable basket, a safety cover therefor having a normal tendency to open, power means for rotating said basket, means controlled by said cover for rendering said power means effective or ineffective upon said basket, means for latching said cover in closed position, and means for actuating said latching means to release the cover at the conclusion of the extracting period.

9. A centrifugal extractor, comprising a rotatable basket, a safety cover therefor having a normal tendency to open, power means for rotating said basket, means controlled by said cover for rendering said power means effective or ineffective upon said basket, means for latching said cover in closed position, and automatic controlling means for said latching means.

10. A centrifugal extractor, comprising a rotatable basket, a safety cover therefor, means normally tending to open said cover, power means for rotating said basket, means controlled by said cover for starting said power means, means for holding said cover in closed position, means adapted to retard rotation of said basket, and means adapted to automatically release said holding means and

thereby subject the cover to the effect of its opening means after said basket retarding means becomes effective.

11. A centrifugal extractor, comprising a rotatable basket, power means for rotating said basket, means for stopping rotation of said basket, timing means for initiating operation of said basket stopping means, and operating means for said timing means arranged to reset the same during the stopping operation.

12. A centrifugal extractor, comprising a rotatable basket, power means for rotating said basket, means for stopping rotation of said basket, timing means for initiating operation of said basket stopping means, and operating means for said timing means whereby the same is reset by the continued rotation of the basket during the stopping operation.

13. A centrifugal extractor, comprising a rotatable basket, a safety cover therefor having a normal tendency to open, power means for rotating said basket, means for stopping rotation of the basket, means for latching said cover in closed position, and means whereby stopping of the basket effects release of said latching means.

14. A centrifugal extractor, comprising a rotatable basket, a safety cover therefor, power means for rotating said basket, means controlled by said cover for rendering said power means effective or ineffective upon said basket, latching means for said cover, timing means for initiating operation of said latching means at the conclusion of the extracting period, and additional means for causing actuation of said latching means at any time.

15. A centrifugal extractor, comprising a rotatable basket spindle, an electric motor having a rotating part attached to said spindle, and automatic timing and brake means actuated by rotation of said spindle and effective upon the circuit connections to said motor at the end of the extracting period to retard spindle rotation.

16. A centrifugal extractor, comprising a rotatable basket, motor means for driving said basket, a cover for said basket having a normal tendency to open, means controlled by said cover for causing said motor to rotate said basket for the extracting operation, and means for automatically stopping said basket at the end of a predetermined extracting period and opening said cover with all parts ready for the next operation.

17. A centrifugal extractor, comprising a rotatable basket, a safety cover therefor having a normal tendency to open, means controlled by closing movement of said cover for automatically maintaining said cover closed and driving said basket for the extracting operation, and timing means adapted at the conclusion of a predetermined ex-

tracting period to automatically retard rotation of the basket to a safe speed, to release said cover to the effect of its normal tendency to open, and to reset itself for the next operation.

18. A centrifugal extractor, comprising a rotatable basket, a safety cover therefor having a normal open position, in combination with basket driving and control means including means for starting the basket rendered effective by closing the cover, and means for stopping the basket after a predetermined period and moving the cover to its open position ready for the next operation.

19. A centrifugal extractor, comprising a rotatable basket, a safety cover therefor having a normal open position, in combination with basket driving and control means including means for starting the basket rendered effective by closing the cover, means

for stopping the basket after a predetermined period and moving the cover to its open position ready for the next operation, and additional means for producing operation at any time during said period of said basket stopping and cover opening means.

20. A centrifugal extractor, comprising a rotatable basket, a guard therefor having open and closed positions, means rendered effective when said guard is in closed position for maintaining it in said position and driving said basket, and means adapted at the conclusion of the extracting period to first retard rotation of the basket to a safe speed and then release said maintaining means and cause the guard to move to open position.

In testimony whereof I hereby affix my signature.

EMIL J. CARROLL.

tracting period to automatically retard rotation of the basket to a safe speed, to release said cover to the effect of its normal tendency to open, and to reset itself for the next operation.

18. A centrifugal extractor, comprising a rotatable basket, a safety cover therefor having a normal open position, in combination with basket driving and control means including means for starting the basket rendered effective by closing the cover, and means for stopping the basket after a predetermined period and moving the cover to its open position ready for the next operation.

19. A centrifugal extractor, comprising a rotatable basket, a safety cover therefor having a normal open position, in combination with basket driving and control means including means for starting the basket rendered effective by closing the cover, means

for stopping the basket after a predetermined period and moving the cover to its open position ready for the next operation, and additional means for producing operation at any time during said period of said basket stopping and cover opening means.

20. A centrifugal extractor, comprising a rotatable basket, a guard therefor having open and closed positions, means rendered effective when said guard is in closed position for maintaining it in said position and driving said basket, and means adapted at the conclusion of the extracting period to first retard rotation of the basket to a safe speed and then release said maintaining means and cause the guard to move to open position.

In testimony whereof I hereby affix my signature.
